UNITED STATES PATENT OFFICE.

SAMUEL R. BAILEY, OF AMESBURY, MASSACHUSETTS.

ADJUSTABLE AXLE-NUT.

SPECIFICATION forming part of Letters Patent No. 623,124, dated April 18, 1899.

Application filed December 14, 1898. Serial No. 699,199. (No model.)

To all whom it may concern:

Be it known that I, SAMUEL R. BAILEY, a citizen of the United States, residing at Amesbury, in the county of Essex and State of Massachusetts, have invented new and useful Improvements in Adjustable Axle-Nuts, of which the following is a specification.

This invention relates to improvements in adjustable axle-nuts especially designed for carriage-axles either with or without ball-bearings for the purpose of setting up from time to time and adjusting the position of the axle-nut relative to the end of the wheel-hub, its washer, or cone-bearing and holding said nut securely in its adjusted position without the employment of check-nuts, as will hereinafter be more fully shown and described, reference being had to the accompanying drawings, wherein—

Figure 1 represents a side elevation of the invention. Fig. 2 represents an end view thereof. Fig. 3 represents a central longitudinal section on the line 3 3, shown in Fig. 1. Fig. 4 represents a cross-section on the line 4 4, shown in Fig. 3. Fig. 5 represents a detail side elevation of the adjustable axle-nut, showing it detached from the axle; and Fig. 6 represents a sectional view showing a modified form of the invention.

Similar letters refer to similar parts wherever they occur on the different parts of the drawings.

In the drawings, A represents the outer end portion of a carriage-axle, and B represents the washer or cone-bearing longitudinally adjustable on said axle end, as usual.

Centrally within the outer end of the axle A is made a longitudinal recess A', the inner end of which is made reduced or tapering, as shown at A" in Fig. 3. The outer end of said recess is provided with an internal screw-thread A³, as shown in said Fig. 3.

C represents the head of the improved axle-nut, which head may be cylindrical, as shown in Fig. 2, and adapted to be adjusted by means of a suitable spanner, or it may be made polygonal for adjustment by means of an ordinary wrench or other suitable tool commonly used for such purpose without departing from the essence of my invention.

The head C is provided with a longitudi-

nally-slotted expansive shank C', the outer end of which is screw-threaded, as shown at C", and made adjustable within the corresponding internal screw-thread A³ in the carriage-axle, as shown in Fig. 3.

The inner ends of the bifurcated or slotted shank C' terminate as two or more preferably tapering lateral projections C³ C³, adapted to be held frictionally in contact with the reduced or tapering recess A" in the axle during the adjustment of the axle-nut, as shown in Fig. 3. It will thus be noticed that the axle-nut shank is held frictionally in position after being adjusted by the pressure of the expansive projections C³ C³ of the slotted or bifurcated shank against the tapering or reduced seat A" in the bored-out axle, thus effectually preventing the nut from working loose by the jarring of the vehicle. Instead of compressing the slotted shank C' C' against the interior bore A' of the axle A it may, if so desired, be forced frictionally against a conical plug or expander A⁴, arranged in the bottom of the recess A', as shown in Fig. 6, by which arrangement the ends of the slotted shank C' C' are caused to be held frictionally in contact with said plug or expander during the adjustment of the axle-nut for the purpose of retaining the latter in its adjusted position, as hereinbefore described. It will be seen that by this arrangement I dispense entirely with the ordinary set-nut usually employed in devices of this kind, and by the arrangement as shown and described the axle-nut can be most easily and quickly adjusted simply by turning a single piece—namely, the head C of the device.

Having thus fully described the nature, construction, and operation of my invention, I wish to secure by Letters Patent and claim—

1. The herein-described adjustable-axle-nut device, consisting in combination with an axle having a longitudinal recess, screw-threaded at its outer end and tapered or reduced at its inner end, a screw-threaded slotted shank adjustable within the screw-thread of the axle and having its open slotted ends adapted to be frictionally held against the inner portion of the axle-recess, substantially as and for the purpose set forth.

2. The herein-described adjustable-axle-

nut device consisting in combination with an axle having a longitudinal recess, screw-threaded at its outer end a screw-threaded slotted shank adjustable within the screw-
5 thread of the axle and adapted to be frictionally held within the recessed axle portion, substantially as and for the purpose set forth.

In testimony whereof I have hereunto set my hand in presence of two subscribing witnesses.

SAMUEL R. BAILEY.
